DESIGN FOR A WHEEL

J Harold Hunt, Lansing, Mich., assignor to Motor
Wheel Corporation, Lansing, Mich., a corpora-
tion of Michigan

Application October 11, 1933, Serial No. 49,450

Term of patent 14 years

To all whom it may concern:

Be it known that I, J HAROLD HUNT, a citizen of the United States residing at Lansing, county of Ingham, State of Michigan, have invented a new, original and ornamental Design for a Wheel, of which the following is a specification, reference being had to the accompanying drawing forming a part hereof.

In the drawing:

Figure I is a side view of a wheel showing my new design;

Figure II is a perspective view of the wheel body shown in Figure I;

Figure III is an enlarged sectional view through one of the spokes taken on substantially the line III—III of Figure I; and

Figure IV is a profile of the wheel taken on substantially the line IV—IV of Figure I.

I claim:

The ornamental design for a wheel as shown.

In testimony whereof he has affixed his signature.

J HAROLD HUNT.
